UNITED STATES PATENT OFFICE

2,035,370

SHINGLE

Norman P. Harshberger, Scarsdale, N. Y., assignor to Bakelite Building Products Co. Inc., New York, N. Y., a corporation of Delaware

Application May 29, 1931, Serial No. 541,090

8 Claims. (Cl. 108—7)

This invention has to do with shingles, more particularly, shingles composed of materials generally employed in the manufacture of so-called prepared rolled roofing, which is made up of a felt-like base saturated with bituminous materials, surfaced with bituminous materials of higher melting point into which are embedded granulated mineral particles.

It is one of the objects of this invention to provide an improved interlocking shingle comprising a plurality of units that will readily interlock in a manner differing from anything heretofore used in the art, and one which will greatly expedite the laying of roofs and coverings for side walls.

It is the further object of this invention to provide an improved roofing material in which the interlocking means are so formed that when the units are being laid on a roof or side wall the engagement of one unit with another takes place in a downward direction, the units being maintained in position by their own weight prior to being nailed down. Heretofore the interlocking engagement of one unit with another was effected from below in an upward direction making it necessary to manually hold the units in place until secured with nails. A more specific object of this invention, however, is to provide a hook like means at one corner, one which does not protrude materially beyond the general border outline of the shingle, and a receiving means also within the outline of the shingle unit, the hook-like portions being formed by cuts and the receiving means also formed by cuts.

The further object of this invention is to provide an improved shingle that when laid in the same course, the interlocking means will co-act at the side lapped portions when the shingles are brought together, to cause the edges thereof to be secured and for the purpose of preventing the wind from turning up the edges thereof.

A further object is to provide shingles of such shape that they will present a design of conventional configuration, and at the same time to eliminate the frills of various attachments that are sometimes employed to secure the edges of shingles.

Still further, and a most important feature of this invention is to provide a locking means that will be difficult to pull loose, or break off, during the application of the shingles, and to provide a nailing range without weakening the securing features of the locking device.

With the above and other objects in view, the improved shingles consist of their whole, or their

parts, and combinations as set forth, and all equivalents thereof.

It is to be understood that nails may be provided to secure these shingles at any desired location that would be covered by an associated shingle.

The annexed drawing and the following description set forth in detail certain mechanism embodying the invention, such disclosed means constituting, however, but one of various mechanical forms in which the principle of the invention may be used.

In the accompanying drawing, the same reference characters designate the same parts in all of the views.

Fig. 1 is a plan view of a blank, forming my preferred shingle; Fig. 2 shows a plan view of a modification, being one type of reversible shingle embodying the same general characteristics of Fig. 1; Fig. 3 shows another plan view of another shingle unit embodying the features of reversibility and the same general interlocking characteristics; Fig. 4 is a plan view of a section of a roof covered with the shingles of Fig. 1; Fig. 5 is a plan view of a modified form showing a different angled outline; Fig. 6 is a section through line 6—6 of Figure 4.

Referring now to the drawing, the numeral 8 designates the exposed portion, and each shingle as cut consists of an exposed portion of a general symmetrical outline.

In Fig. 1, the numeral 9 designates the downwardly protruding hook-like lug which is formed by the inwardly extending slot or slit 21. The cut forming the opening which cooperates with the lug 9 is designated by the numeral 10. The exposed edge 11 is indicated as extending at right angles to a longitudinal edge 12 which is the bottom exposed edge, and the covered lapped portion 13 when assembled on the roof or side wall is shown in Fig. 4.

In Fig. 2, numerals 14 and 14' designate what may be either the exposed lower edge or the upper covered edge. Lug 9 and cut 10 are adapted to co-act with similar shingles when assembled on the roof with either edge 14 or 14' being exposed to the weather, depending upon whether the shingles are being laid from left to right, or from right to left.

In Fig. 3, a re-arrangement of locking lugs 9 and 9', and receiving means, or openings 20 and 20', is illustrated, and this shingle has the same reversible characteristics as that of Fig. 2, except that it is adapted to be laid in one sidewise direction.

Fig. 4 is a section of a roof, while showing only the shingle illustrated in Fig. 1, designates the method of adapting all the Figs. 1 to 5 to the roof or side wall surface, the same numerals in each figure designating the function of the portions shown in Fig. 4.

In none of the known prior art is there shown a shingle having a locking corner means within the general border outline of the shingle, and 10 having the same adapted to co-act for locking registration in such a novel and practical manner as disclosed in this invention. Further, in no instance is there disclosed in the prior art a shingle that is so well adapted for locking engagement as by hooking-in, in the direction that 15 the succeeding shingles are applied. This manner of locking engagement has been found to be extremely advantageous to the roofer, because the lug 9 is generally less damaged in shipment, and 20 when handled by the roofer, therefore, is less apt to break off because it does not protrude beyond the lower or side edges, as shown in the prior art, particularly as in such patents as those to Theilacker No. 1,710,954; Harshberger No. 25 1,718,933; Theilacker No. 1,725,551; Finley No. 1,604,745 or Harshberger No. 1,657,082.

Referring now to the modification shown in Fig. 5, it will be noted that the diagonally disposed side edge 15' and the bottom or weather 30 edge 12, are at acute angles, and while this is not my preferred form there are some advantageous features in this type by reason of a better side edge angle which affords better protection from angularly driven snow and rain.

35 Other modes of applying the principle of my invention may be employed instead of the one explained, change being made as regards the mechanism herein disclosed, provided the means stated by any of the following claims or the equivalent of such stated means be employed.

40 I therefore particularly point out and distinctly claim as my invention:—

1. A shingle having a receiving means wholly surrounded by the material of the shingle, and 45 a locking lug in oblique relation to an axis of the shingle and to the longitudinal axis of said receiving means, said shingle adapted to be assembled with the locking lug entered through the said receiving means of an adjacent shingle 50 and one edge of said locking lug providing a stop for disengagement of the interlocking parts when movement of said locking lug is attempted in a direction normal to said axes.

2. A shingle having a locking lug along an edge 55 thereof and in oblique relation to said edge, and receiving means wholly surrounded by the material of the shingle and adapted to receive the locking lug of a similar shingle in assembly to create an interlock substantially inseparable to 60 movement of the shingle normal or parallel to said shingle edge.

3. A shingle having a receiving means adja-

cent to a boundary edge and at one end of the shingle, said receiving means wholly surrounded by the material of the shingle, and a locking lug at the other end of the shingle along said boundary edge and in oblique relation to said edge. 5

4. A shingle having an elongated receiving means spaced from a shingle edge, said receiving means wholly surrounded by the material of the shingle and having its longitudinal axis in the general direction of said shingle edge, and a locking lug on said shingle obliquely disposed to said axis, said shingle adapted to be assembled with other similar shingles with their receiving means axes substantially parallel and with the locking lug of one shingle entered through the receiving means of an adjoining shingle to create an interlock substantially inseparable to movement of the shingles normal or parallel to said axis of the receiving means. 15

5. A shingle having a slot in one edge obliquely disposed thereto determining the lock edge of a locking lug, and receiving means wholly surrounded by the material of the shingle spaced therefrom and adapted to receive the locking lug of another in assembly to create a substantially inseparable interlock to movement normal or parallel to said shingle edge. 20

6. A shingle having slots in opposite edges, said slots determining locking lugs each obliquely disposed to its respective edge, and said shingle 30 having lug-receiving means wholly surrounded by the material of the shingle adapted to receive a locking lug of a similar shingle in locking engagement to create an interlock substantially inseparable to movement of the shingles normal to 35 said locking lug edge.

7. An assembly of shingles, each having a locking lug at a lower corner, and lug receiving means wholly surrounded by the material of the shingle in an adjacent corner and adapted to receive 40 a locking lug of an adjoining shingle, said shingles assembled with similar shingles in a longitudinal course with the lower edges of the shingles substantially parallel and interlocked; said locking lugs entered through the receiving means 45 of adjoining shingles and positioned beneath the material surrounding said receiving means.

8. An assembly of shingles each having at a lower weather corner a locking lug determined by an edge slot and another edge of the shingle, 50 and in an adjacent weather corner a lug receiving means wholly surrounded by the material of the shingle and adapted to receive the lug of an adjoining shingle, said shingles assembled in a longitudinally extending course with adjacent shingles in lapped relation and with the locking lug in the lower weather corner of one shingle entered through the receiving means of an adjoining shingle and positioned beneath the material surrounding said receiving means. 55

NORMAN P. HARSHBERGER.
